Primary Examiner — Marianne Pandozzi(74) *Attorney, Agent, or Firm* — Thedford I. Hitaffer; Hitaffer & Hitaffer, PLLC(57) **CLAIM**

The ornamental design for a shaker bottle, as shown and described.

DESCRIPTION

FIG. 1 is a front view of the shaker bottle, in a closed position, with the top and the bottom of the shaker bottle separated.

FIG. 2 is a rear view of the shaker bottle shown in FIG. 1.

FIG. 3 is a top plan view of the shaker bottle shown in FIG. 1. FIG. 4 is a right side elevational view of the shaker bottle shown in FIG. 1, with the left side being the mirror image thereof.

FIG. 5 is a front view of the shaker bottle with the lid in open position;

FIG. 6 is a rear view of the shaker bottle shown in FIG. 5.

FIG. 7 is a top plan view of the shaker bottle shown in FIG. 5; and,

FIG. 8 is a right side elevational view of the shaker bottle shown in FIG. 5, with the left side being the mirror image thereof.
